SEAL FOR ROTARY DRIERS OR COOLERS

John L. Erisman, Oak Park, Ill., assignor to Link Belt Company, a corporation of Illinois

Application February 1, 1946, Serial No. 644,753

8 Claims. (Cl. 285—96.1)

1

This invention relates to new and useful improvements in seals for rotary dryers or coolers. Dryers or coolers of the type broadly covered by the Gustav Bojner et al. Patent No. 1,709,456, issued April 16, 1929, each involves a rotatable, horizontal cell or cylinder which is provided with an annular series of longitudinal passages at its inner periphery. The hot or cold treatment fluid is delivered to these passages at one end of the revolving cell or cylinder by means of a stationary distributor head or ring. This head or ring is provided with a fluid delivery duct that spans an area which is approximately equal to the combined area of only a limited number, for example two to four, of the adjacent open ends of the longitudinal fluid passages and is further constructed so that it closes the open ends of all of the remaining longitudinal fluid passages. Of course, as the cell or cylinder rotates, the open ends of all of the annular series of longitudinal fluid passages successively move into and out of register with the fluid delivery duct of the stationary distributor head or ring with the result that the treatment fluid is delivered only to the ends of the longitudinal fluid passages that are arranged at any given moment beneath the bed of material being dried or cooled in the central treatment chamber of the rotating cell or cylinder. Because the distributor head or ring is of annular formation in elevation and it is essential that the hot or cold treatment fluid be prevented from leaking to the surrounding atmosphere either at the zone where it is delivered to the longitudinal fluid passages underlying the bed of material or throughout the region of the remaining longitudinal fluid passages which are not registering with the delivery duct for being supplied with the treatment fluid, sealing means must be provided to close the gaps or spaces left at the joints between the inner and outer peripheries of the stationary distributor head or ring and the associated portions of the rotatable cell or cylinder. To be practical and efficient, the sealing means must possess the two essential characteristics of being readily serviced at least insofar as the replacement of wearable parts is concerned and of being capable of rendering satisfactory service for a substantial period of time when operating under either high or low temperature conditions.

It is the primary object of this invention to provide extremely efficient sealing means for preventing the escape of hot or cold treatment fluids through the joints between stationary distributor heads or rings and rotatable cells or cylinders of dryers or coolers,

2

Still another primary object of the invention is the provision of sealing means which is so constructed that the parts receiving the greatest amount of wear easily and quickly may be replaced and the entire sealing means will render long and satisfactory service when operating under either high or low temperature conditions.

A further object of the invention is the provision of combined labyrinth and floating ring seals for closing the joints between the stationary distributor head or ring and the rotatable cell or cylinder of a dryer or cooler.

Other objects and advantages of the invention will be apparent during the course of the following description.

In the accompanying drawings forming a part of this specification and in which like numerals are employed to designate like parts throughout the same,

Figure 1 is an elevational view of the feed end of a rotatable cell or cylinder type of dryer or cooler embodying this invention.

Figure 2 is a fragmentary, vertical sectional view taken on line 2—2 of Fig. 1.

Figure 3 is a fragmentary, vertical sectional view taken on lines 3—3 of Fig. 1.

Figure 4 is a fragmentary, sectional view taken on line 4—4 of Fig. 1.

Figure 5 is a fragmentary, sectional view taken on line 5—5 of Fig. 1.

Figure 6 is a fragmentary, sectional view taken on line 6—6 of Fig. 1.

Figure 7 is a fragmentary sectional view taken on line 7—7 of Fig. 1.

Figure 8 is a detail perspective view of a spring clip that is further illustrated in Figs. 3 and 4, and

Figures 9 and 10 are perspective views of driving and spring lugs, respectively, which are further illustrated in Figs. 2, 3, 4 and 5.

In the drawings, wherein for the purpose of illustration is shown the preferred embodiment of this invention, and first particularly referring to Fig. 1, the reference character 11 designates in its entirety the base frame of a rotary dryer or cooler embodying this invention. This base portion carries suitable supporting rolls 12, by means of bearing blocks 13, for engaging the annular trucks 14 secured to the periphery of a rotatable dryer or cooler cell or cylinder. The cell or cylinder is illustrated in this figure as including an end feed plate 15, having a central feed opening 16, which is fastened to the cell or cylinder to rotate therewith.

Although not illustrated in this Fig. 1, the rotatable cell or cylinder is provided with an an-

nular series of longitudinally extending fluid passages adjacent its inner periphery. These fluid passages receive the hot or cold treatment fluid through the feed duct 17 that is flared at its inner end 17a to span a desired number of the adjacent open ends of the longitudinal fluid passages. This feed duct is carried by the distributor head or ring 18 that is adjustably supported by means of the lateral attachment plates 19 to the vertical standards or posts 20 that are carried by the base frame 11. Bolts 21 are received in slots 22 of the attachment plates 19 to accommodate this adjustment of the distributor head or ring 18 relative to the adjacent end of the rotatable dryer or cooler cell or cylinder.

By referring to Figs. 2 and 3, it will be seen that the rotatable cell or cylinder is provided with an exterior, cylindrical wall portion 23 that is substantially coaxially arranged with reference to an outer peripheral wall portion 24 of the stationary distributor head or ring 18. These two figures also illustrate the rotatable cell or cylinder of the dryer or cooler as including an annular wall portion 25 that is concentric with the exterior wall portion 23 and is located substantially in angular alignment with the inner periphery of the annular series of longitudinal fluid passages. To further illustrate the location of this annular inner wall portion 25, it will be noted that the periphery of the end plate 15 of the dryer or cooler cell or cylinder is attached to this wall portion 25. These two figures also disclose the stationary distributor head or ring 18 as being provided with an annular wall portion 26 that is concentric with its exterior wall portion 24 and is arranged substantially coaxially of the cell or cylinder wall portion 25.

Figs. 2 and 3 are taken on the section lines illustrated in Fig. 1 and, for that reason, are located at portions of the distributor head or ring which close the adjacent ends 27 of longitudinal fluid passages. For that reason, the distributor head or ring 18 is provided with a plate 28 that lies between the annular wall portions 24 and 26.

By an inspection of Figs. 2 and 3, it will be seen that the hot or cold treatment fluid would be permitted to escape to the surrounding atmosphere if suitable sealing means were not provided for closing the gaps or openings formed by the joints between substantially axially aligned wall portions 23 and 24 and between the substantially axially aligned wall portions 25 and 26. In other words, leakage can occur both at the inner periphery and the outer periphery of the distributor head or ring 18 where it cooperates with opposed portions of the rotatable dryer cell or cylinder. For that reason, two annular seal structures must be provided for closing these two joints. Because these two annular seal structures are identical in many respects, the descriptions of the two structures will be combined or consolidated as much as possible.

Each one of the seal structures includes a labyrinth type of seal and a floating ring type of seal which cooperates with the labyrinth seal by closing the gap or opening left by the latter seal.

The labyrinth seal portion of each one of the two seal structures includes a labyrinth seal ring 29 that is illustrated in the several figures as being welded to a wall portion of the distributor head or ring 18. It is to be understood, however, that this labyrinth seal ring can just as readily be welded to a wall portion of the rotatable cell or cylinder. This labyrinth seal ring is provided with an annular radially extending face 30 that

is machined to provide a true, smooth surface. The labyrinth seal also includes a labyrinth seal band 31 that is secured to the remainder of the two substantially coaxial wall portions. This labyrinth seal band 31 is illustrated as being attached to the wall portion of the rotatable cell or cylinder because the labyrinth seal ring 29 is illustrated as being attached to the wall portion of the stationary distributor head or ring. However, these labyrinth seal members may be reversed so that the labyrinth seal band would be attached to the wall portion of the stationary distributor head or ring 18.

The labyrinth seal band 31 is arranged so as to overlap the gap or space formed by the joint between the coaxial wall portions of the distributor head or ring 18 and the cell or cylinder of the dryer or cooler. The concentrically arranged labyrinth seal band is of greater internal diameter than either of the wall portions with which it is associated. This greater diameter is provided for the purpose of allowing for some misalignment of the associated wall portions. The labyrinth seal band may be of proper angular formation in radial section to allow for the mounting of one circumferential edge portion on one of the coaxially aligned wall portions while leaving the remainder of the sealing band spaced from the other wall portion. However, it is preferable to employ an annular filler member 32 in combination with a truly cylindrical seal band 31. The filler member 32 is welded to its associated wall portion and the labyrinth seal band 31 is suitably welded to its filler member 32. These labyrinth seal rings and bands 29 and 31, respectively, are provided for both the inner and the outer joints between the stationary distributor head or ring 18 and the rotatable cell or cylinder. For that reason, the same reference characters will be employed for the labyrinth seal elements of both joints. It will be noted that the labyrinth seal bands and the labyrinth seal rings form a tortuous path for retarding leakage of treatment fluid through either joint. The gaps or openings left by the labyrinth seals, therefore, must be closed by additional sealing means. This additional sealing means, which can be broadly described as floating ring sealing means, now will be specifically disclosed.

Concentrically associated with the exterior surface of the labyrinth seal band 31, associated with the joint formed by the wall portions 23 and 24, and concentrically associated with the inner surface of the labyrinth seal band 31, associated with the joint between the wall portions 25 and 26, are the two pairs of floating rings 33, 34, 35 and 36. The floating rings 33 and 35 each has suitably welded to its inner face the annular keeper band 37. By particularly inspecting Figs. 2, 3, 6 and 7, it will be seen that the spaced floating rings 33—34 or 35—36, their associated keeper bands 37, and their associated labyrinth seal bands form annular grooves or spaces for receiving and compressing packing rings 38. Each one of these packing rings 38 is to be tightly compressed against its associated exterior or interior surface of a labyrinth seal band 31 to prevent leakage of treatment fluid between these ring and band members 38 and 31 respectively. Any suitable flexible packing material can be employed for forming the rings 38.

For the purpose of sealing between the machined inner faces of the labyrinth seal rings 29 and their opposed floating rings 33 and 35,

sealing rings 39 are provided. These rings may be made of any suitable material, such as special bronze, copper, wood, or the like. The sealing rings 39 are secured to the floating rings 33 and 35 by a suitable number of bolts 40. These bolts pass through openings formed in the rings 33 and 35 and are threaded into openings formed in the sealing rings 39. Because of the relative angular movement that will take place between the labyrinth seal rings 29 and the sealing rings 39 that bear against the machined faces 30 of the rings 29, the sealing rings 39 and 29 will be subject to the only wear that will occur in these sealing structures. For that reason, the sealing rings 39 can be readily replaced by merely removing their retaining bolts 40.

It will be appreciated that the labyrinth seal rings 29 and the special bronze, copper or wood sealing rings 39 just as readily could be connected by the bolts 40. If that were the case, the sealing rings 39 would have to bear against and partake of relative angular movement with respect to the floating rings 33 and 35.

For the purpose of drivingly attaching the two pairs of floating rings 33-34 and 35-36 to their associated cell or cylinder wall portions 23 and 25, a suitable number of driving pins 41 are secured by welding in openings provided to receive the same in the floating rings 33 and 35. These driving pins 41 also pass through aligned openings formed in the floating rings 34 and 36 and are received in the notches 42 of the driving lugs 43 that are attached by welding to the wall portions 23 and 25. These driving pins and lugs 41 and 43, therefore, cause the floating rings 33 to 36 inclusive to rotate with the dryer or cooler cell or cylinder. Of course, if the labyrinth seal rings 29 and bands 31 were reversed with respect to their associated wall portions, so that the labyrinth seal rings would be carried by the wall portions of the rotatable cell or cylinder, the driving lugs 43 would be attached to the stationary wall portions 24 and 26 of the distributor head or ring 18 and their associated driving pins 41 would hold the floating rings 33 to 36 and the sealing rings 39 against rotation, or stationary with the distributor head or ring 18.

It is necessary to so apply spring pressure that the sealing rings 39 will be forced against the labyrinth seal rings 29, and so that the floating rings 34 and 36 will be forced toward their associated floating rings 33 and 35, respectively, to compress the two packing rings 38 against their associated labyrinth seal bands 31. Because slightly different spring pressure applying mechanisms are employed for the outer and inner sealing structures, these spring mechanisms will be described separately.

Figs. 3, 4 and 8 best illustrate the spring structures provided for the outer seals. Each one of these outer spring structures includes a spring end seating pin 44 that is welded in place in an opening formed in the floating ring 34. The compression spring 45 has one of its ends seated on the associated pin 44. The remaining end of each compression spring 45 is seated on a threaded adjusting stud 46. Each stud has pinned to the intermediate portion of the same a nut 47 that bears against the adjacent end of its compression spring 45.

An angle-iron ring 48 is welded to the exterior of the wall portion 23. This angle-iron ring is provided with notches 49 at suitable intervals to freely accommodate the adjusting studs 46 and their fixed nuts 47. For the purpose of spanning each one of these notches 49, a spring

clip 50 is provided. These spring clips are welded to the inner face of the angle-iron ring 48 with fillers 51 interposed. Each one of these spring clips 50 is provided with an internal, threaded opening 52 for connection with its associated spring adjusting stud 46. Consequently, by rotating the studs 46 in the proper direction, they will be adjusted axially with respect to their spring clips 50 for moving the spring adjustment nuts 47 to further compress the springs 45. A lock nut 52 is threaded on each spring stud 46 and functions to retain the stud in any desired adjusted position.

Figs. 3 and 5 disclose the spring devices for the inner floating ring seal structure. Each one of these spring devices includes a spring seating pin 54 that is welded in a receiving opening formed in the cell or cylinder feed plate 15. Each one of these pins seats the end of a compression spring 55. The remaining end portion of each spring 55 is seated on an associated end of a spring adjusting stud 56. A spring abutment nut 57 is pinned to each one of the studs 56. A spring lug 58 is provided for each spring stud 56 and is welded to one face of the floating ring 36. Each one of these spring lugs is provided with an internally threaded opening 59 for threaded connection with its associated spring stud 56. A locking nut 60 cooperates with the threaded lug 58 and the threaded stud 56 for locking the stud in any desired adjusted position. By rotating the stud relative to its lug, the compression spring 55 may be adjusted.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a device of the type described, the combination with a rotary cell or cylinder having an annular wall portion and a stationary head having an annular wall portion arranged substantially coaxially of the first wall portion to provide a radially directed gap therebetween, of means for sealing the gap between said wall portions, comprising means directly mounted on and extending circumferentially of substantially axially aligned annular surfaces of said wall portions, respectively, forming a labyrinth seal for said radially directed gap, and means forming a floating contact seal for closing the outer portion of the opening of said labyrinth seal.

55

2. In a device of the type described, the combination with a rotary cell or cylinder having an annular wall portion and a stationary head having an annular wall portion arranged substantially coaxially of the first wall portion to form a radially directed gap therebetween, of means for sealing the radial gap between said wall portions, comprising a labyrinth seal band mounted on and extending circumferentially of one surface of one of said wall portions and telescopically associated with the corresponding surface of the other annular wall portion, a labyrinth seal ring carried by said corresponding surface of said other annular wall portion normal to said labyrinth seal band and in axially spaced relation to the free edge of the latter, and means forming a floating seal for closing the open space between said labyrinth seal band and ring.

60

3. In a device of the type described, the combination with a rotary cell or cylinder having

65

70

75

an annular wall portion and a stationary head having an annular wall portion arranged substantially coaxially of the first wall portion to form a radially directed gap therebetween, of means for sealing the radial gap between said wall portions, comprising means directly mounted on and extending circumferentially of substantially axially aligned annular surfaces of said annular wall portions, respectively, forming a labyrinth seal for said radially directed gap, means forming a floating seal for closing the outer portion of the opening of said labyrinth seal, said floating seal means comprising a packing ring bearing against the means of the labyrinth seal that is carried by the surface of one of said annular wall portions, a sealing ring bearing against the means of the labyrinth seal that is carried by the corresponding surface of the other of said annular wall portions, and means for carrying said packing and sealing rings.

4. In a device of the type described, the combination with a rotary cell or cylinder having an annular wall portion and a stationary head having an annular wall portion arranged substantially coaxially of the first wall portion to form a radially directed gap therebetween, of means for sealing the radial gap between said wall portions, comprising means directly mounted on and extending circumferentially of substantially axially aligned annular surfaces of said annular wall portions, respectively, forming a labyrinth seal for said radially directed gap, means forming a floating seal for closing the outer portion of the opening of said labyrinth seal, said floating seal means comprising a packing ring bearing against the means of the labyrinth seal that is carried by the surface of one of said annular wall portions, a sealing ring bearing against the means of the labyrinth seal that is carried by the corresponding surface of the other of said annular wall portions, means for carrying said packing and sealing rings, means for attaching said ring carrying means to one of said annular wall portions, and means for applying spring pressure against the ring carrying means in the direction to force the sealing ring tightly against its associated labyrinth seal means.

5. In a device of the type described, the combination with a rotary cell or cylinder having an annular wall portion and a stationary head having an annular wall portion arranged substantially coaxially of the first wall portion to form a radially directed gap therebetween, of means for sealing the radial gap between said wall portions, comprising a labyrinth seal band mounted on and extending circumferentially of one surface of one of said annular wall portions and telescopically associated with the corresponding surface of the other annular wall portion, a labyrinth seal ring carried by the surfaces of said other annular wall portion normal to said labyrinth seal band and in axially spaced relation to the free edge of the latter, means forming a floating seal for closing the open space between said labyrinth seal band and ring, said floating seal means comprising a packing ring bearing against the periphery of the labyrinth seal band, a sealing ring bearing against the labyrinth seal ring, and means for carrying said packing and sealing rings.

6. In a device of the type described, the combination with a rotary cell or cylinder having an annular wall portion and a stationary head having an annular wall portion arranged substantially coaxially of the first wall portion to form a radially directed gap therebetween, of means

for sealing the radial gap between said wall portions, comprising a labyrinth seal band mounted on and extending circumferentially of one surface of one of said annular wall portions and telescopically associated with the corresponding surface of the other annular wall portion, a labyrinth seal ring carried by the surface of said other annular wall portion normal to said labyrinth seal band and in axially spaced relation to the free edge of the latter, means forming a floating seal for closing the open space between said labyrinth seal band and ring, said floating seal means comprising a packing ring bearing against the periphery of the labyrinth seal band, a sealing ring bearing against the labyrinth seal ring, means for carrying said packing and sealing rings, means for attaching said ring carrying means to the annular wall portion carrying the labyrinth seal band, and means for applying spring pressure against the ring carrying means in the direction to force the sealing ring tightly against the labyrinth seal ring.

7. In a device of the type described, the combination with a rotary cell or cylinder having an annular wall portion and a stationary head having an annular wall portion arranged substantially coaxially of the first wall portion, of means for sealing the joint between said wall portions, comprising a labyrinth seal band carried by one of said wall portions and telescopically receiving the substantially coaxially associated other wall portion, a labyrinth seal ring carried by said other wall portion normal to said labyrinth seal band and in spaced relation to the free edge of the latter, a pair of spaced floating rings surrounding said labyrinth seal band, a keeper band carried by one of the floating rings in the space between it and the other floating ring, a packing ring positioned in the space formed by the pair of floating rings and the labyrinth seal and keeper bands, a sealing ring carried by one of the floating rings for bearing against the adjacent face of the labyrinth seal ring, spring means for applying force against said floating rings to compress the packing ring against the labyrinth seal band and for pressing the sealing ring against the labyrinth seal ring, and means for attaching the floating rings to the wall portion carrying the labyrinth seal band.

8. In a device of the type described, the combination with a rotary cell or cylinder having an annular wall portion and a stationary head having an annular wall portion arranged substantially coaxially of the first wall portion, of means for sealing the joint between said wall portions, comprising a labyrinth seal band carried by one of said wall portions and telescopically receiving the substantially coaxially associated other wall portion, a labyrinth seal ring carried by said other wall portion normal to said labyrinth seal band and in spaced relation to the free edge of the latter, a pair of spaced floating rings surrounding said labyrinth seal band, a keeper band carried by one of the floating rings in the space between it and the other floating ring, a packing ring positioned in the space formed by the pair of floating rings and the labyrinth seal and keeper bands, a sealing ring carried by one of the floating rings for bearing against the adjacent face of the labyrinth seal ring, a plurality of pins attached at one end to the floating ring carrying the sealing ring and projecting through aligned openings formed in the other floating ring, a lug for engaging the free end of each pin attached to the wall portion carrying the lab-

yrinth seal band, and spring means for applying force against the floating ring having the pin receiving openings for compressing the packing ring against the labyrinth seal band and for pressing the sealing ring against the labyrinth seal ring. 5 JOHN L. ERISMAN.
